US00D895651S

(12) **United States Design Patent** (10) Patent No.: **US D895,651 S**
Lee et al. (45) Date of Patent: ** Sep. 8, 2020

(54) **DISPLAY SCREEN OR PORTION THEREOF WITH GRAPHICAL USER INTERFACE**

(71) Applicant: **SAMSUNG ELECTRONICS CO., LTD.**, Suwon-si, Gyeonggi-do (KR)

(72) Inventors: **Heonwoo Lee**, Seoul (KR); **Hanna Kim**, Seongnam-si (KR); **Yoonho Lee**, Incheon (KR)

(73) Assignee: **SAMSUNG ELECTRONICS CO., LTD.**, Gyeonggi-do (KR)

(**) Term: **15 Years**

(21) Appl. No.: **29/648,170**

(22) Filed: **May 18, 2018**

Related U.S. Application Data

(63) Continuation of application No. 29/584,997, filed on Nov. 18, 2016, now Pat. No. Des. 819,685.

CLAIM

The ornamental design for a display screen or portion thereof with graphical user interface, as shown and described.

DESCRIPTION

The FIGURE is a front view of a display screen or portion thereof with graphical user interface, showing our new design.

The broken lines illustrating portion of the graphical user interface form no part of the claimed design.

The outermost broken lines illustrating the display screen or portion thereof form no part of the claimed design.

The solid black shading of the outer portion in FIGURE illustrates a contrast in appearance between the claimed portions.
